UNITED STATES PATENT OFFICE.

WILLIAM H. MAKUTCHAN, OF CHICAGO, ILLINOIS.

SPARK-PLUG.

1,293,843.

Specification of Letters Patent. Patented Feb. 11, 1919.

Application filed April 19, 1918. Serial No. 229,551.

To all whom it may concern:

Be it known that I, WILLIAM H. MAKUTCHAN, a citizen of the United States, residing at Chicago, in the county of Cook and 5 State of Illinois, have invented a new and useful Spark-Plug, of which the following is a specification.

The device forming the subject matter of 10 this application is a spark plug, and one object of the invention is to provide a structure of this kind which will be simple in construction, the chance of the plug becoming out of order being extremely remote, and the construction being such that the 15 plug will not be likely to be put out of commission, even in the hands of an inexperienced operator.

The invention aims to improve the mounting of the electrodes and to improve generally and to enhance the utility of devices 20 of that kind to which the present invention appertains.

In the accompanying drawings:—

Figure 1 shows in side elevation, a spark 25 plug constructed in accordance with the invention;

Fig. 2 is a longitudinal section of the plug, wherein parts appear in elevation; 30 And Fig. 3 is a perspective of the support which carries one electrode.

In carrying out the invention, there is provided a body 1, preferably made of metal, including a wrench head 2 and a reduced extension 3 which is externally 35 threaded as shown at 4, so that the body may be assembled with the cylinder of an internal combustion engine. The body 1 is provided with an enlarged axial passage 5. Superposed on the upper end of the 40 body 1 is a disk 6 which is made of insulating material. A support 7 is mounted on the disk 6 and includes a foot plate 8 and a reduced neck 9, the foot plate being in immediate contact with the insulating disk 5. Openings 10 are fashioned in the foot 45 plate 8 of the support. Insulating washers 11 are supported on the foot plate 8 and metal washers 12 are supported on the insulating washers 11. Securing devices 14, 50 which may be screws, pass downwardly through the washers 12 and 11 and through the opening 10 in the foot plate 8 of the

support 7, the securing devices passing through the insulating disk 6 and engaging the upper end portion of the body 1. The 55 heads 15 of the securing devices 14 coöperate with the washers 12, and in this connection it is to be observed that the diameter of the openings 10 in the foot plate 8 are relatively large, compared with the 60 diameter of the securing devices 14. Consequently, the securing devices 14 do not come into contact with the foot plate 8, and there is no danger of a short-circuit at this point. An electrode 16 in the form of a 65 rod, is carried by the support 7 and extends downwardly through the axial passage 5 of the body 1 in spaced relation with the body, the electrode rod passing through the insulating disk 16. An electrode 17 is mounted 70 in the lower end of the part 3 of the body 1 and coöperates with the electrode 16.

The invention comprises a connector 18, preferably in the form of a resilient metal plate, having elongated slots 19 defining end 75 strips 20 and an intermediate strip 21, the plate 18 having an opening 22, adapted to receive a conductor (not shown). The upper end of the electrode 16 may be inserted through the slot 19, the end strips 20 and 80 the intermediate strip 21 upon the other hand binding upon the electrode 16. The construction is such that the connector may be mounted readily and with equal facility 85

The spark plug forming the subject matter of this application is simple in construction and includes but few parts, having no loose elements, and practically nothing about the device which is likely to get out of 90 order even though the structure be submitted to somewhat rough usage, or be manipulated by those unaccustomed to the handling of electrical devices. The plug may be fashioned at trifling expense, and the parts there- 95 of are so shaped that any of them may be renewed without difficulty and at small cost.

Having thus described the invention, what is claimed is:—

A spark plug comprising a body having 100 a passage; a support including a foot plate and a reduced neck, the foot plate having an opening; insulating material between the body and the foot plate; a securing device

2
insulated from the foot plate and passing through the opening, in spaced relation with the wall of the opening, the securing device engaging the body; and an electrode carried by the neck and extended into the passage.

In testimony that I claim the foregoing

as my own, I have hereto affixed my signature in the presence of two witnesses.

WILLIAM H. MAKUTCHAN.
